UNITED STATES PATENT OFFICE

99,832

DESIGN FOR A SCOOP

Rex M. Shultz, Ventura, Calif.

Application February 25, 1936, Serial No. 61,338

Term of patent 3½ years

To all whom it may concern:

Be it known that I, Rex M. Shultz, a citizen of the United States of America, residing at Ventura, in the county of Ventura and State of California, have invented a new, original, and ornamental Design for a Scoop, of which the following is a specification, reference being had to the accompanying drawing forming part thereof.

In the drawing:

Fig. 2 is a view in side elevation of the same.

Fig. 3 is a view looking at the front end of the scoop.

Fig. 4 is a section on the line 4—4 of Fig. 1.

I claim:

The ornamental design for a scoop, as shown.

REX M. SHULTZ.
